David G. Galbraith
Inventor

UNITED STATES PATENT OFFICE.

DAVID G. GALBRAITH, OF MINERAL WELLS, TEXAS.

CLAMP FOR HOLDING FILES, BUNDLES, AND SUCH LIKE.

Application filed July 21, 1920. Serial No. 397,842.

To all whom it may concern:

Be it known that I, DAVID G. GALBRAITH, a citizen of the United States, residing at Mineral Wells, in the county of Palo Pinto and State of Texas, have invented a new and useful Improvement in Clamps for Holding Files, Bundles, and Such like, of which the following is a specification.

My invention relates to the improvements 10 in paper clamps, in which a desired spring wire is formed in the shape of an equi-angular triangle in general outline, and the object of my improvement is, to provide open reversible set spring jaws which converge from a common base, having inturned 15 free ends, each end being doubled back to contact with the adjacent side of the triangle substantially midway of its length, the jaws crossing a slight distance from the doubled 20 ends.

I attain this object by the device illustrated in the accompanying drawing, in which—

Figure 1 is a plan view showing the complete set spring jaws;

Fig. 2 shows the jaws formed before being stretched to produce the set spring shown in Fig. 1;

Fig. 3 is an end view of the open set 30 spring jaws;

Fig. 4 shows the jaws closed by reversing Fig. 3.

Similar numerals refer to similar parts throughout the several views.

The device has the shape of an equiangular triangle and comprises a base 1, converging bends 2—2, extended converging set spring jaws 3—3, with in-turned bends 4—4, the free ends being doubled back to contact

at 5—5 with the jaws 3—3 substantially 40 midway of the sides of the triangle, as shown in Fig. 1.

When the clamp is in open position as shown in Fig. 3, the jaws are not in contact but are a short distance apart. In this condition the clamp is placed on a paper file. If the thickness of the file, or package of papers is less than one-third the length of the base 1, the clamp should be reversed, by turning the base through an angle of 180 45 degrees, thereby closing the clamp and increasing the clamping pressure as shown in Fig. 4. When placed on a file having a thickness from one-third to two-thirds the length of the base 1, the clamp should not 50 be reversed. When removing the clamp from a thick file, it should not be reversed, but with a slight twist of the base it can be pulled off. The ends being turned in and 55 contacting with the jaws substantially midway of their length do not scratch the paper when the clamp is being applied or removed.

I claim:

1. A paper clamp formed of spring wire, and having substantially the shape of an 60 equiangular triangle, said clamp comprising a base, converging spring jaws at the ends of the base, the free end of each jaw being turned in and doubled back to contact with said jaw substantially midway of its length, 65 the jaws crossing a slight distance from the doubled ends.

2. A paper clamp as claimed in claim 1, in which the jaws at the point of crossing are a short distance apart, whereby clamping pressure may be increased by turning the clamp through an angle of 180 degrees.

DAVID G. GALBRAITH.
